UNITED STATES PATENT OFFICE.

GEORGE C. THIESEN, OF JERSEY CITY, NEW JERSEY.

DESIGN FOR A DISH.

SPECIFICATION forming part of Design No. 36,259, dated March 31, 1903.

Application filed February 20, 1903. Serial No. 144,342. Term of patent 3½ years.

To all whom it may concern:

Be it known that I, GEORGE C. THIESEN, a citizen of the United States, residing at Jersey City, Hudson county, State of New Jersey, have invented and produced a new, original, and ornamental Design for Dishes, of which the following is a specification, reference being had to the accompanying drawings, forming a part thereof.

Figure 1 is a plan view of a dish showing my new design, and Fig. 2 is a longitudinal section thereof.

As shown in the drawings, the leading or material feature of my design consists of a leafy effect and a representation of a lobster. The leafy effect is produced by a number of representations *a* of lettuce-leaves, which are ribbed and fluted for representing the veins and to represent the wrinkles, creases,

or folds of the natural leaf. The representation *b* of a lobster is spread upon the leaves *a*, and a portion of the body is humped up at *c* to furnish a handle for the dish.

The rim *d* of the dish has the irregular wavy outline of the edges of the leaves. 25

Having thus described my invention, what I claim as new, and desire to secure by Letters Patent, is—

The ornamental design for a dish, substantially as shown and described. 30

In testimony whereof I have signed this specification in the presence of two subscribing witnesses.

GEORGE C. THIESEN.
